UNITED STATES PATENT OFFICE.

BOYD W. GOEBEL, OF JONESVILLE, SOUTH CAROLINA.

CONVERTIBLE CHAIR.

Application filed September 13, 1922. Serial No. 588,027.

To all whom it may concern:

Be it known that I, BOYD W. GOEBEL, a citizen of the United States, residing at Jonesville, in the county of Union and State 5 of South Carolina, have invented new and useful Improvements in Convertible Chairs, of which the following is a specification.

In carrying out the present invention it is my purpose to provide a chair which may 10 be converted from a straight chair into a reclining chair, a bed, a child's crib, a "kiddie coop" for infants, etc., and wherein the component parts will be so arranged and correlated as to enable the chair to be converted with a minimum effort and within 15 a short time.

It is also my purpose to provide a convertible chair which will embrace the desired features of simplicity, efficiency and 20 durability and which may be manufactured and marketed at small cost.

With the above recited objects in view, and others of a similar nature, the invention resides in the construction, combination and 25 arrangement of parts set forth in and falling within the scope of the appended claims.

In the accompanying drawings:

Figure 1 is a perspective view of a convertible chair constructed in accordance with 30 my invention.

Figure 2 is a vertical sectional view therethrough.

Figure 3 is a sectional view on the line 3-3 of Figure 2.

Figure 4 is a view showing the chair as converted into a reclining chair, parts being shown in section and parts in elevation.

Figure 5 is a vertical sectional view showing the chair converted into a "kiddie coop."

Figure 6 is a sectional view showing the chair as converted into a bed.

Figure 7 is an enlarged fragmentary sectional view showing the mounting of the 45 cushions.

Figure 8 is a sectional view on the line 8-8 of Figure 6.

Referring now to the drawings in detail, 50 1-1 designate vertical posts of the back of the chair. These posts are spaced apart in parallelism and are of suitable height and are connected together at their upper ends by means of a horizontal cross bar 2. In advance of the back posts 1, respectively, 55 are relatively short posts 3 at the front of the chair and connecting the upper ends of

the front posts 3 with the rear posts 1 are arm rests 4. Between the posts 1 and 3 and below the arm rests 4 are panels 5, respectively, that form the sides of the frame of 60 the chair.

Secured to the confronting surfaces of the sides of the chair are horizontal guide rails 6 that extend from the front of the chair to 65 the back.

Arranged within the space between the side panels of the chair is a substantially rectangular receptacle 7 comprising a bottom wall 8, vertical side walls 9-9 and a front wall 10. The front wall 10 is of solid 70 construction, while the side walls 9-9 and the bottom wall 8 are foraminous, as clearly shown in Figures 2, 3 and 5 of the drawings. The upper end of this receptacle 7 is closed 75 by a solid top 11 and the forward edge of this top 11 is hinged, as at 12, to the front wall 10.

The side walls 9-9 of the receptacle 7 at their rear edges are connected to the forward edges of vertical bars 13-13 that lie parallel 80 so with the inner surfaces of the respective rear posts 1-1 and terminate at the upper ends short of the cross bar 2 and at their lower ends contiguous to the bottom 8 of the receptacle. The upper and lower ends of the 85 bars 13 are connected together by horizontal bars 14-14, respectively; and extending over the front portion of the frame formed by the bars 13 and 14 is a strip 15 of canvas or other suitable material, this strip being 90 fastened to the bars 13 and 14. The lower portion of this canvas strip acts to close the rear end of the receptacle 7, as clearly shown in Figure 5 of the drawings.

The vertical bars 13-13 are equipped respectively on their outer sides with trunnions 16-16 that fit into the respective guide rails 6 and in the normal position of the receptacle and the frame formed by the bars 13 and 14 the forward edge of the bottom of the receptacle fits into a rabbet 17 formed in the upper surface of a horizontal cross bar 18 that connects the front posts or legs 3 at their lower ends, as clearly illustrated in Figures 4 and 5 of the drawings. 95 Thus, the frame composed of the bars 13 and 14 and the receptacle 7 connected to such frame are maintained in normal positions within the frame of the chair formed by the front and rear posts and the side 100 panels, as clearly illustrated in Figures 1 and 2 of the drawings.

Arranged in advance of the frame formed of the bars 13 and 14 above the receptacle 7 is a frame 19 that is composed of horizontal end bars and vertical side bars that lie parallel with the end bars 14 and the side bars 13. This frame 19 is pivoted at its upper end, as at 20, to the top horizontal bar 14, as shown in Figure 5, so that the frame 19 will be normally maintained parallel with the frame formed of the bars 13 and 14. This frame 19 is braced by an intermediate cross bar 21 and its front side, that is, the side facing toward the front of the chair, is equipped with a pad 22 of some suitable material which constitutes the back of the chair. The frame 19 also carries legs 23 which, in the present instance, are pivoted, respectively, as at 24, to the side bars of the frame 19 adjacent to the lower ends thereof. The legs 23 normally lie within the frame 19, as shown by the dotted lines in Figure 5. Legs 25 are also pivoted at their upper ends to the vertical bars 13, respectively, adjacent to the upper ends of such bars.

Pivoted to the top 11 of the receptacle adjacent to the rear edge of such top and the respective side edges thereof are legs 26 that normally lie against the top, as shown in Figure 3 of the drawings, and mounted upon the top 11 when in normal position is a cushion 27, while fixed to the outer side of the front wall 10 of the receptacle is a cushion 28. This cushion 28 is fixed to the front wall 10 of the receptacle by means of eyelets 29 in the rear side cushion engaging over prongs 30 carried by the front wall 10, as clearly illustrated in Figure 7 of the drawings.

In practice, the parts are normally in the position shown in Figures 1 and 2 of the drawings, and in this position a straight chair is provided, the pads 27 and 22 forming the side and back rest, respectively.

To convert the chair into a reclining chair the frame composed of the bars 13 and 14 is swung rearwardly about the trunnions 16 to the position shown in Figure 4 of the drawings, and in this position the frame is locked by means of links 31 that are pivoted, respectively, to the inner sides of the rear posts 1 and engage in pins 32 carried by the vertical bars 13.

To convert the chair into a bed, the frame formed of the bars 13 and 14 is swung about the trunnions 16 to a horizontal position and slid forwardly between the side panels of the main frame of the chair, so that the trunnions lie at the forward ends of the guide members 6, as clearly shown in Figure 6 of the drawings. In this position of the frame formed by the bars 13 and 14 the receptacle 7 is arranged in the position shown in Figure 6, and when in this position screen sections 33 that are hinged to the upper edges of the side walls 9—9 of

the receptacle 7 and normally lie within such receptacle parallel with the side walls thereof, as shown in Figure 3 of the drawings, are swung downwardly to positions coextensive with the side walls 9 of the receptacle. The top 11 is also swung through a one-quarter revolution, so as to lie coextensive with the front wall 10, as in Figure 6. The frame 19 is now swung to a position co-extensive with the frame formed by the bars 13 and 14 and the legs 25 and 23 are engaged with the ground or floor. Thus, a bed is provided as in Figure 6 and owing to the screen sides of such bed the head end thereof may be projected through a window if desired.

To convert my improved chair into a "kiddie coop" the pad 27 is removed and the top 11 swung through a one-half revolution to the position shown in Figure 5, the legs 26 engaging the floor. Thus, the infant may be placed within the receptacle and the top 11 forms a table.

I have entered into a detailed description of the construction and relative arrangement of parts embraced in the present and preferred embodiment of my invention with a view to imparting a full, clear and exact understanding of the said embodiment. I do not desire, however, to be understood as confining myself to the said specific construction and relative arrangement of parts, inasmuch as in the future practice of my invention such changes or modifications may be made as fairly fall within the scope of my invention as defined by my appended claims.

Having thus described the invention, what is claimed as new, is:—

1. A convertible chair comprising a main frame formed of vertical rear posts and vertical front posts of less height than said rear posts, arm rests between said rear and front posts respectively, side panels between said rear and front posts and below said arm rests, a movable receptacle within the space between said panels and designed to form a receptacle for bed clothing, a frame connected to the rear of said receptacle and comprising vertical side bars lying parallel with said rear posts respectively, cross bars connected with said vertical bars, trunnions projecting outwardly from said vertical side bars, guideways carried by the inner sides of said panels and receiving said trunnions whereby said frames and receptacle may be swung to provide a reclining chair and also swung to horizontal position and moved forwardly to provide a bed, such receptacle having a foraminous bottom wall and foraminous side walls and also a foraminous screen carried by each said foraminous side wall respectively and cooperating therewith and with the bottom wall to provide a screened hood for said bed.

2. A convertible chair comprising a main frame formed of vertical rear posts and vertical front posts of less height than said rear posts, arm rests between said front and rear posts respectively, side panels between said front and rear posts respectively and below said arm rests, a movable receptacle within the space between the said panels and designed to form the bottom of the chair, and a receptacle for bed clothing, a frame connected to the rear of said receptacle and comprising vertical side bars lying parallel with said rear posts respectively, and cross bars connected with said vertical bars, trunnions projecting outwardly from said vertical side bars, guideways carried by the inner sides of said panels and receiving said trunnions whereby said frame and receptacle may be swung to provide a reclining chair and swung to a horizontal position and moved forwardly to provide a bed, a horizontal top for said receptacle normally forming the bottom of said chair and movable through one-half revolution to open said receptacle and form a table whereby a "kiddie coop" may be provided.
- 10

In testimony whereof I affix my signature.

BOYD W. GOEBEL.
